UNITED STATES PATENT OFFICE.

JOHN S. MUCKLÉ AND THOMAS H. STRALEY, OF PHILADELPHIA, PENNSYLVANIA,
ASSIGNORS TO STANDARD ELEVATOR INTERLOCK COMPANY, OF PHILADELPHIA,
PENNSYLVANIA, A CORPORATION OF PENNSYLVANIA.

INTERLOCKING MECHANISM FOR ELEVATORS.

1,175,794.

Specification of Letters Patent. Patented Mar. 14, 1916.

Application filed December 5, 1913. Serial No. 804,790.

To all whom it may concern:

Be it known that we, JOHN S. MUCKLÉ and THOMAS H. STRALEY, citizens of the United States, residing in Philadelphia, county of Philadelphia, State of Pennsylvania, have invented certain Improvements in Interlocking Mechanism for Elevators, of which the following is a specification.

Our invention relates to certain improvements in interlocking mechanism for elevators which prevents the door from being opened when a car is not at a landing, and also prevents the movement of a car after it has been brought to a stop at a landing and the door has been opened.

The invention is particularly adapted for use in connection with elevators of the type in which an operating cable extends through the car and an operator grasps the cable to actuate the mechanism for starting and stopping the car, in contradistinction to an operating device consisting of an operating wheel or lever.

One object of our invention is to provide means for limiting the movement of the cable when the door has been opened, and to permit of the free movement of the cable when the door is closed.

A further object of the invention is to construct the mechanism so that it will act upon the return run of the cable.

In the accompanying drawings:—Figure 1, is a sectional view showing the door closed and the mechanism shifted to allow the operating cable to have a free movement; Fig. 2, is a similar view, showing the door partly open and the mechanism shifted so as to interfere with the free movement of the operating cable; Fig. 3, is a sectional view through the car and part of the elevator well on the line *a—a*, Fig. 1; Fig. 4, is a sectional view on the line *b—b*, Fig. 1; Fig. 5, is a sectional view on the line *c—c*, Fig. 1; Fig. 6, is a sectional view on the line *c'—c'*, Fig. 2; Fig. 7, is a sectional view on the line *d—d*, Fig. 5; Fig. 8, is a sectional view showing the latch for the door; Fig. 9, is a front view of said latch; and Fig. 10, is a view of a modification.

Referring to the drawings, 1, 1 are the walls of the elevator well of the ordinary construction. 2 is one of the platforms.

3 is the platform door, which is a laterally sliding one in the present instance, but it will be understood that it may be a door arranged to slide vertically without departing from the essential features of the invention.

4 is the car having a floor 5, as shown in Fig. 3.

6 is the operating cable, one run of which passes through the car while the return run, as shown in Fig. 1, is located in the space between the car and the wall of the elevator shaft. The operator stands in the car and grasps the cable so as to shift the mechanism controlling the movement of the car.

Depending from the forward end of the door 3 is an arm 7 having a notched extension 8, which is engaged by the latch 9 pivoted at 10 to the plate 11, which is secured to the wall of the elevator well. A spring 13 on the latch bears against the plate and forces the latch out against a stop band 14, as clearly shown in Figs. 8 and 9. When the latch 9 engages the extension 8, the door is locked in the closed position. This latch can be released by a foot pin 15 in the floor of the car which actuates a bell crank lever 16 pivoted at 17 and connected by a rod 18 to an arm 19 having a roller 20, which bears against the latch 9. A spring withdraws the arm 19 out of contact with the latch as soon as the foot is taken off the pin 15.

In the present instance, secured to the wall of the elevator well, directly under the door opening, is a sliding bolt 22. This bolt has a head 23, which is engaged by the arm 7 when the door is closed, but, when the door is open, the arm is withdrawn from the bolt and the bolt is free to move independently of the door.

24 is a bearing secured to the wall of the elevator well, as shown in Figs. 1, 2 and 6, and this bearing has a guideway for a sliding plate 25 made as shown in Figs. 5, 6 and 7. This plate has two arms 27, in the present instance, and on each arm is a spring 28 confined between a pin on the arm and the bearing, so that the tendency of the sliding plate is to move away from the bolt.

On the return run of the operating cable stops 29 and 29^a are mounted and the passage 30 in the bearing 24 is of such a size

as to allow the stops to move freely therethrough. The passage is preferably tapered at the top and bottom, as in Fig. 7.

The plate 25 is connected to the bolt 22 by a chain 31 and the opening 32 in the plate is formed, in the present instance, by spacing the arms 27 a sufficient distance apart to make the opening the same size as the opening in the bearing, in order to 10 allow a clear passage through the bearing when the parts are in the position illustrated in Figs. 1 and 5, but, when the door is opened and the bolt is released, the springs 28 move the plate to such a position 15 that it reduces the opening. A stop 33 limits the movement of the plate, so that while the opening will be greater in diameter than the cable, it will be less than the stops 29 and 29^a, and if the cable is moved, said stops 20 will come in contact with the plate. This movement, however, is not sufficient to shift the mechanism for starting the car, consequently, the car cannot be accidentally raised or lowered until the door is closed and the 25 opening in the plate is enlarged to allow one of the stops to pass. Thus it will be seen by the above construction that the door is locked when the elevator is at a landing, as it is held by the latch 9 and the latch 30 cannot be operated until the car is at a landing, as the mechanism for actuating the latch is carried by the car.

When a car is at a landing and the door has been opened by pressing the foot on the 35 foot pin 15, the sliding plate is released from the control of the door and its springs will shift it so as to reduce the passage in the bearing 24, and while the cable is free to move through the opening one of the 40 stops on the cable will come in contact with the plate and will prevent further movement of the cable, consequently, the mechanism for starting the car cannot be actuated.

In Fig. 10, we have illustrated a modification in which the bolt 22 is dispensed with and the chain 31 is connected directly to the 45 arm 7^a on the door 3^a, but we prefer to use the construction illustrated in Fig. 1, as it makes the cable mechanism entirely independent of the door. The peculiar form of 50 door latch and the mechanism on the car for

actuating the latch may be modified without departing from the spirit of the invention.

We claim:—

1. The combination with an elevator car 55 adapted to an elevator well, of a platform, a sliding door arranged to close the opening leading from the platform to the well, a cable having its return run extending between the car and the wall of the elevator 60 well, stops on said cable, an arm on the door, a bolt on the wall of the elevator well adjacent each landing and in the path of said arm, a bearing mounted adjacent each landing on the wall of the elevator 65 well and having an opening for the passage therethrough of said return run of the cable, a horizontal forked plate slidably mounted in said bearing, a spring for moving the plate in one direction, and a chain connecting the plate with the bolt and of such a length that the plate will be shifted to open the passage in the bearing when the arm on the door engages the bolt when in its closed position, so that when the door is 70 open the plate will be in position to restrict the opening of the bearing and thereby limit the movement of the cable by contact with a stop; the closing of the door shifting the plate and leaving the opening in the bearing 75 free for the movement of said cable.

2. The combination in a device for preventing the movement of the cable of an elevator when the car is at a landing and the door is open, consisting of a bearing 80 arranged to be secured to the wall of the elevator well and having a vertical passage therethrough; a forked sliding plate mounted in the bearing; a spring on the fork of the plate to move it in one direction; and means for moving it in the opposite direction, the plate being arranged to regulate the size of the passage through the bearing.

In testimony whereof, we have signed our 95 names to this specification, in the presence of two subscribing witnesses.
